Primary Examiner—M. N. Pandozzi

(57) CLAIM

The ornamental design for a mug with gaming device, as shown.

DESCRIPTION

The claimed mug with gaming device is used for drinking as well as playing games of chance and fortune telling.

FIG. 1 is a front elevational view of a mug with gaming device showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof; and,

FIG. 8 is a perspective dismantling view thereof with the electronic component and the display ring being pulled out.

1 Claim, 5 Drawing Sheets
